(57) **CLAIM**

The ornamental design for a picture frame, as shown and described.

DESCRIPTION

FIG. 1 is a top plan view of a picture frame.

FIG. 2 is a front elevation view of the picture frame shown in FIG. 1.

FIG. 3 is a bottom-right perspective view of the picture frame shown in FIG. 1.

FIG. 4 is a bottom-left perspective view of the picture frame shown in FIG. 1.

FIG. 5 is a left elevation view of the picture frame shown in FIG. 1.

FIG. 6 is a top-right perspective view of the picture frame shown in FIG. 1.

FIG. 7 is a top-left perspective view of the picture frame shown in FIG. 1.

FIG. 8 is a right elevation view of the picture frame shown in FIG. 1.

FIG. 9 is a bottom plan view of the picture frame shown in FIG. 1; and,

FIG. 10 is a rear elevation view of the picture frame shown in FIG. 1.

The dash-dot-dash broken lines, in FIG. 10, represent a boundary line within the picture frame which forms no part of the claimed design.

1 Claim, 10 Drawing Sheets
